DREDGE BUCKET

William H. Stires, High Bridge, N. J., assignor to
Taylor-Wharton Iron & Steel Company, High
Bridge, N. J., a corporation of New Jersey

Application December 18, 1934, Serial No. 758,118

2 Claims. (Cl. 37—141)

My invention relates to dredge bucket and lip assemblies of the type in which the parts are engageable for swinging mounting of the lip whereby it may be postured in a simple and expeditious manner and be readily removed for purposes of repair or replacement, the object of the invention being to so order and arrange the parts that the lip mounting and interlocking instrumentalities are locked externally of the bucket.

10 The nature, characteristic features and scope of the invention more readily will be understood from the following detailed description taken in connection with the accompanying drawing, forming a part hereof, wherein:—

15 Figure 1 is a central vertical sectional view of a dredge bucket and lip assembly embodying my invention.

Fig. 2 is a section on line 2—2 of Fig. 1.

Fig. 3 is a detail of the front lock, and

20 Fig. 4 is a section on line 4—4 of Fig. 1.

According to the invention, the dredge bucket 5 is provided on its rim with a lip seat 6 and externally and below the same with lip bearings 7, the number of which may vary, although I find three to be sufficient, one on the front of the bucket, the others either side thereof. Also externally of the bucket and nearer the back thereof are cored areas 8 in part contributed by a bolstered or substantially reinforced angularly directed overhang or upper wall 9.

30 The lip 10 has a medially shouldered portion 11 fitted to the rim seat and a continuous skirt or apron 12 whose thrust is taken by the lip bearings 7 so that when the lip is seated its skirt is lapped by the members 7.

35 The ends 13 of the lip are directed downwardly and rearwardly and are of substantially V-form and are so related to the cored pockets 8 that when the lip is in upraised position its substantially pointed ends may be inserted in the cored

pockets and fulcrumed on the bottoms thereof to swing the lip to its seat whereupon the ends are interlocked with the pockets.

It is desirable to employ a quick-acting interlock at the front of the bucket and externally thereof and such interlock may embody a rib 14 on the middle lip bearing and a cooperating bifurcated rib 15 on the lip, said ribs having registered apertures to accommodate a wedge fastening 16.

Having described the invention, what is claimed as new is:—

1. A dredge bucket and lip assembly of the rivetless type comprising, in combination, a bucket having external abutments and receptacles for cooperation with the lip, a swingable lip having a skirt to engage the abutments and elbow-like terminals to engage the receptacles, said receptacles having bottoms lying in a substantially horizontal plane to support the extremities of the terminals and permit them to move back into locking engagement with the receptacle walls when the lip is swung downwardly to operative position.

2. A dredge bucket and lip assembly of the rivetless type comprising, in combination, a bucket having a rim seat and external abutments and receptacles below the same, a swingable lip having an offset shouldered portion to engage the rim seat, a skirt to engage the abutments, and elbow-like terminals with relatively sharp V ends, said receptacles having substantially horizontally directed abutments which support the V ends and permit them to move back into locking engagement with the receptacle walls when the lip is swung downwardly to operative position, and auxiliary means for holding the lip to its seat.

WILLIAM H. STIRES.
